DISPLAY STAND

Filed Jan. 27, 1928

UNITED STATES PATENT OFFICE

HENRY L. GRIFFITH, OF MINNEAPOLIS, MINNESOTA

DISPLAY STAND

Application filed January 27, 1928. Serial No. 249,854.

My invention has for its object the provision of a simple and highly efficient display stand, intended for general use but especially adapted for use in displaying jars of goods, such as pickles and the like, said goods to be sold by the jar or in bulk from the jars containing the same.

By the use of my improved stand, pickles may be sold in bulk or in hermetically sealed containers in a novel and attractive manner. Said stand, while occupying a very few square feet of floor space, is designed to hold an entire stock of pickles in a very compact space but at the same time attractively display the same in a manner in which the containers may be individually removed from the stand or replaced thereon without disturbing the other containers on the stand. The bulk pickles are sold from large-mouthed containers in which the pickles are originally packed and hermetically sealed. These large-mouthed containers enable a merchant to remove the pickles therefrom by the use of a fork or ladle without having to lift the pickles out of an unsanitary keg or barrel, as bulk pickles are now sold, which often causes a loss on account of spoilage.

To the above end, generally stated, the invention consists of the novel devices and combinations of devices hereinafter described and defined in the claims.

In the accompanying drawings, which illustrate the invention, like characters indicate like parts throughout the several views.

Referring to the drawings:

Fig. 1 is a perspective view of the display stand with a jar of goods supported on the table thereof;

Fig. 2 is a view of the display stand in transverse vertical section with some parts broken away and illustrating a jar of goods on each of the shelves thereof;

Fig. 3 is a perspective view of the casing removed from the table and with the door of the casing removed;

Fig. 4 is a fragmentary detail view in section taken on the line 4—4 of Fig. 2, on an enlarged scale, with one of the jars shown in full;

Fig. 5 is a perspective view of the false shelf; and

Fig. 6 is a fragmentary detail view principally in section showing the false shelf supported on one of the shelves of the casing.

The numeral 7 indicates a square table top having at its corners four supporting legs 8 and at its edge an upstanding marginal retaining flange 9 in the form of a hollow square. Removably supported on the table top 7 is a casing 10 having shelves 11 in its front in stepped arrangement. Said casing 10 at its base is of such length as to snugly fit between opposite members of the retaining flange 9 with its back engaging the respective member of said retaining flange as a stop. This casing 10 has a width substantially half of that of the table 7 so as to leave a space on the table 7 in front of said casing for the display of goods in front thereof. By arranging the retaining flange 9 in the form of a hollow square it is possible to place the casing 10 on the table 7 so that it will face in any one of four different positions and at the same time be held against endwise or backward movement on the table 7 by the retaining flange 9.

The risers for the shelves 11, as shown, are made progressively lower from the table 7 up and said shelves, as shown, are made progressively narrower from the bottom shelf up. The casing 10 has a back section 12 which extends upward from the top shelf 11 for a considerable distance and not only forms a back for the top shelf 11 but has ample space for advertising matter. The sides of the casing 10 extend above the shelves 11 at the ends thereof and their upper edges are inclined from the bottom shelf 11 to the back section 12.

The shelves 11 have upstanding relatively wide retaining flanges 13 at their outer longitudinal edges and the inner surfaces of said flanges are inclined, for a purpose that will presently appear. On the bottom of the casing 10 at the front and sides thereof are inturned supporting flanges 14 which rest directly on the table 7. Wing nut-equipped bolts 15 are passed through aligned holes in the top of the table 7 and flanges 100

14 detachably secure the casing 10 to the table 7. The casing 10 affords a storage compartment 16 for surplus goods of the kind displayed on the table 7 and shelves 11.

5 The open back of the casing 10 is normally closed by a sliding door 17 held in place by guides 18 at the rear vertical edges of the sides of the casing 10. As shown, goods contained in jars *x* are placed on the shelves 11 for display and these goods are to be sold by the jar. The jars *y* on the shelves 11 decrease in size from the bottom shelf up and said jars are held in place on said shelves by the sides of the casing 10 and retaining flanges 13.

10 Relatively large jars *y*, only one of which is shown, are placed on the table 7 in front of the casing 10 and contain goods to be sold in bulk therefrom. The cover-equipped necks for the jars *y* are relatively large so that the goods may be easily removed therefrom with a fork or ladle.

15 The jars *x* on the shelves 11 are illuminated at night by an electric light bulb 19 within the compartment 16 back of the shelves 11 and back of which is a reflector 20. Light passages 21 are formed in the inclined inner surfaces of the flanges 13 and light passages 22 are formed in the riser of 25 the lower shelf 11. Obviously, the light from the bulb 19 passing through the light passages 21 will produce a flood light on the jars *x* and the light passing through the passages 22 will illuminate the jars *y* and 30 thereby give the entire display a pleasing appearance. A suitable switch for the light bulb 19 will be provided, but for the purpose of this case it is not thought necessary to illustrate the same.

35 40 In case certain of the jars are of a low type and it is desirable to raise the same in order to give the display a better appearance, there is provided a false shelf 23 having at its front and rear longitudinal edges short 45 legs 24 and at its outer longitudinal edge an upstanding retaining flange 25. The false shelf 23 is of such length as to snugly fit between the sides of the casing 10 above the shelf 11 on which it is placed and between 50 the respective retaining flange 13 and riser, as shown in Fig. 6.

55 In actual usage false shelves of the type shown in Fig. 5 will be provided in different widths for the several shelves 11. The compartment 16 affords ample space for the storage of surplus goods of the type displayed on the stand. By making the table 7 and casing 10 separable, the same may be shipped or stored in relatively compact form and facilitates the handling thereof. The above described display stand has, in actual usage, proven highly efficient for the purpose had in view.

60 What I claim is:

65 1. A display table having an upstanding

70 marginal retaining flange, a casing having enclosed sides removably mounted on the table within the retaining flange and held thereby against lateral or rearward movements, the sides of said casing being adapted to extend substantially flush with the flanged sides of said table, said casing having a front side stepped to provide shelves and spaced from the retaining flange at the front of the table to leave a portion of the top of the table in front of the casing and within the retaining flange to form a lowermost step consecutive with the series of shelves supported thereby for the display of goods.

75 2. A display table comprising a flanged top and shelves supported on said top and arranged in stepped relation from said top, said shelves having supporting side plates adapted to telescope with the flanged sides of said top and stopping short of the forward flanged edge thereof.

80 3. A display device comprising a casing having shelves arranged in stepped relation, said shelves having upstanding retaining flanges at their outer longitudinal edges, said flanges having apertures opening into said casing, whereby a source of light supported within said casing will be reflected through said apertures and directed on the surface of the goods displayed on said shelves.

85 4. The structure defined in claim 2 including means for permitting rays of light from a light source within the cabinet to illuminate articles displayed on said shelves.

90 In testimony whereof I affix my signature. 100
HENRY L. GRIFFITH.
